Solomon Anderson of Perth Amboy New Jersey
Letters Patent

The subscriber is a citizen of the State of New Jersey and making part of the same containing a description in the words of the said Solomon Anderson Annex himself of his improvement in the Lock.

To all to whom these presents shall come, Solomon Anderson, M.D. of the City of Perth Amboy in the County of Middlesex and State of New Jersey sends greeting. Be it known that I Solomon Anderson have invented constructed made and applied to use a new and useful improvement in locks, and which said improvement is specified by reference to the plate annexed and in the words following to wit.

Fig 1 represents the plate of the lock without its cap and the pins of the lock. A. the head of the bolt. B the tail of the bolt C a stamp revolved or otherwise firmly fastened into the tail of the bolt the shape of which is, shown in the plate and which stamp extends or projects nearly to the cap of the lock. D a diamond shaped stamp revolved or attached firmly to the plate of the lock above the tail of the bolt and extending to the cap or through it. E a round stamp revolved or attached firmly to the side of the lock behind the bolt and extending through the cap. These stamps are made of steel or even of any other suitable material, and the two stamps C and E are very similar to those used in other locks, i.e. notch made into the lower edge of the bolt behind the back tail in order to notches the back tail so that it shall break off when undue force is applied to open the lock. Fig 2 a tumblers made of steel steel or iron or other suitable material having a groove or slot in the back end of it marked F instead of a round hole as is a common tumbler, which groove or slot is to allow the tumbler to slide upon the round stamp. Fig 1. as will hereafter more fully appear. The said tumbler has also a notch or rack as it is sometimes called by locksmiths in the other end, or fore end marked G similar to the common tumbler which notch is filled and adapted to the stamp C. Fig 1. allowing the said bolt stamp C to pass out of a

into the said notch or rack as the bolt is thrown out or thrown back by the key when the tumbler is properly lifted and which notch is so constructed as to hold said ^{part} the said tumbler ^{part} by the weight of one end of the tumbler resting on the ^{part} stamp ^{part} so as to be drawn out by the said stamp with the bolt when not lifted by the key the said pin ^{part} is so constructed as to allow of such sliding motion to the tumbler on the stamp ^{part} Fig 1. The said tumbler has also a fine or projection on its upper edge marked ^{part} A which fine or projection is formed between notches in the said upper edge of the tumbler at the intervening portion of projection constituting the said fin. This fine or projection is so situated or placed on the upper edge of the tumbler as to be immediately behind the stamp ^{part} D. Fig 1. When the tumbler is placed in the lock with the bolt thrown back and immediately before the said stamp ^{part} D. when the bolt is thrown out and the tumbler drawn out with it as herein before described. The use of the said fin is to prevent the bolt being thrown back by the said fin striking against the stamp ^{part} D. Fig 1. When the tumbler is lifted after being drawn out with the bolt, the lower edge of the tumbler is marked ^{part} B is straight not concave nor convex as is the case in the usual or common tumbler where the key acts upon it. In the usual tumblers of one lock all the lower edges of them correspond and are similar so as to form a smooth and regular or even surface particularly in that part or portion of them exposed to the key hole or where the key acts upon them and in the several tumblers of one lock all the notches of the notches marked ^{part} C. Fig 2. are placed at different heights ^{or placed} in their several positions so that the said tumblers shall require to be lifted to different heights or distances to allow the bolt stamp ^{part} to pass into or out of the several notches. Fig 3. The key without any bits and the end or key pin being square and marked ^{part} D. and having a nut ^{part} E. turned on the extreme end of it. which nut is ground and forms a part of the key pin and corresponds inclinately with the round shoulder ^{part} H of the said key pin from whence the key pin originates. Figures 4. 5. 6. & 7. 8. 9. The bits with a square heel in each will fit to the upper part of the key pin so as to be held in

and taken off at pleasure. One of the bits, fig. 9, is to be placed on one end of the square part of the key pin, fig. 1, and always to remain there when the key is used until ready to lift one of the numbered tumbler pins or ordinary tumblers, and consequently must always be lifted. The other bit, fig. 10, is made thicker and stronger than the others, it is to be placed on the other end of the square part of the key pin and is intended to work against the sides of the bolt to move the bolt out or in. The other or intervening bits, Figures 6, 7, 8 are numbered as in the plate and are intended to lift or raise the bits in described grooved or changeable tumblers. Their sizes and of different lengths, each one adapted to a particular tumbler, being longer or shorter as the corresponding tumbler on which it acts requires to be lifted more or less to allow the bolt stamping C to pass out of or into the notch H, and each one numbered 5 corresponds with its respective tumbler in order to show its relative place on the key. The numbers increase commencing at the shoulder of the key pin, as, a matter of convenience. (I sometimes mark them 6, 7, 8, with characters in the glyptics. Figures 10, 11, 12, 13 (lings) or blanks fitted to the square part of the key pin of the same diameter as the end and shoulder of the key pin and of the same thickness as the numbered or changeable bits. One of these lings is to be put upon the key pin to fill up the space when a bit is taken off.

Fig. 14, a table of combinations or changes, to show the different forms of which the key is susceptible and to find the operator in removing the key he was in looking by reference to the register number. Each combination is numbered in the marginal column a check number. I call Register numbers (see plate fig. 14.) The number of changes in a lock will of course depend upon the number of grooved or changeable tumblers it contains, and their corresponding numbered bits. A Fig. 8, a lever which works upon a round stamping T, and shown in its proper place with lock exploding forwards, beyond the end of the tumblers when in their natural position, and having a bar H attached to the end of it which bar is at right angles with the lever.

and extends from the plate of the lock to the cap directly across the upper edge of the tumblers when they are drawn out by the bolt. There is also attached to this lever a curved wire or rod U. which projects through the upper arm of the lock, and moves freely through it when the lever is lifted or depressed, or the end of the bar U may project through the plate of the lock and move freely in a curved groove made for the purpose. The lever, retained in a horizontal position it is, left either up or down by a spring which rests upon the back end of it. This lever with its fixtures I call a detector, its use is to show whether a false key or an improper instrument has been introduced into the key hole and the tumblers lifted. Should one or more of the tumblers be drawn out with the bolt when the lock is locked, each tumbler or tumbler will pass underneath the bar U. of the lever U. Fig 1. and if either of the tumblers so drawn out are then lifted the bar and lever will also be lifted and remain in that position which will be detected by the end or wire U. sum projecting through the iron of the lock. The lever may then be returned to its former position by pressing upon the end of the wire U. so as to begin ^{again} to be again operated on by a false key. In these locks I seldom make less than six changeable or grooved tumblers, and sometimes as many as twenty, which latter number gives more than a million of changes, and I do construct the locks that no two shall be alike nor have a similar key unless especially ordered, making the tumblers and their corresponding bits, or key bits, more or less in number in every lock, or of different thicknesses or to have more or less in weight or more or less difference in the rising or lifting of the several tumblers of each lock, and by the different relative positions of the tumblers having the several different lifts in different locks.

I claim as my invention the groove or slot in a tumbler as heretofore set forth by means of which groove or slot the tumblers admit of two distinct motions or operated or not operated on by the key. I claim as my invention the pin or projection on the upper edge of the tumbler together with the stamp against which the

said false projection striking and much resistance when the tumblers is improperly operated upon by the key or other instrument. I claim as my invention the semicircular or straight and even and regular edges of the several tumblers in one lock forming a regular surface in that part or portion of the cut placed to the key hole where the key operates upon them which the notches or notching in the face edge of them are so constructed in relation to the bolt stump as to require the said tumblers to be lifted to different heights or distances in order to allow the bolt stump to pass into the said notches when the bolt is thrown back by which regular and even face of the lower edge of the tumblers, a false impression is given as to the formation of the key.

I claim as my invention the discontinuity in the length of the bits of a key when operate upon the semicircular even and regular face edges of the tumblers, but not so as to correspond with the irregular notches of the notches on the tumblers at the bolt stump where no impression of them can be taken through the key hole.

I claim as my invention the manner of changing the key by taking off the bits and substituting others instead thereof by which blank spaces left in the key the tumblers corresponding to those absent bits are not lifted when the key is turned, and by which change in the key the lock is locked differently, and so that no other formation of the same key will unlock the lock.

I claim as my invention the table for having or combining as hereinbefore set forth as applied to the purpose of changing the key to a lock.

I claim as my invention the herein before described detector for ascertaining whether a false key or other improper instrument has been applied to the lock to trip the tumblers.

And I further claim as my invention the aforesaid application of the several parts of the herein before described lock, and I also claim as my invention the notching the back talon of the bolt so that it shall break off when too much force is applied to force open the lock.

In testifying that the above is a true specification of my said

improvement as above described, I have cause to lay my hand this the 11th day of November in the Year of our Lord one thousand Eight hundred and Thirty Six.
